(57) **CLAIM**

The ornamental design for a flashlight, as shown and described.

DESCRIPTION

FIG. 1 is a top, front and right side perspective view of a flashlight in accordance with our new design;

FIG. 2 is a top, rear and left side perspective view of the flashlight in accordance with our new design;

FIG. 3 is a front elevational view of the flashlight in accordance with our new design;

FIG. 4 is a rear elevational view of the flashlight in accordance with our new design;

FIG. 5 is a top plan view of the flashlight in accordance with our new design;

FIG. 6 is a bottom plan view of the flashlight in accordance with our new design;

FIG. 7 is a right side elevational view of the flashlight in accordance with our new design;

FIG. 8 is a left side elevational view of the flashlight in accordance with our new design; and,

FIG. 9 is a top, front and right side perspective view of the flashlight in accordance with our new design illustrating a state in which an irradiation part of the flashlight is tilted and a battery is attached the flashlight.

The broken line showing of environment in FIGS. 1, 3, 4, 6, 8 and 9 is for illustrative purposes only and forms no part of the claimed design.

The oblique line shading illustrates a translucent or transparent portion of the flashlight through which the environment shown in the broken lines may be visible as illustrated in FIGS. 1, 3 and 9.
